GEORGE J. SEGAL, OF PHILADELPHIA, PENNSYLVANIA.

APPARATUS FOR EXHIBITING MERCHANTISE.

Application filed October 6, 1927. Serial No. 224,422.

This invention relates to an apparatus for displaying merchandise intended for sale, and more particularly to an apparatus which is operable to automatically and successively 5 present a series of articles such as rugs and the like, before the view of a prospective purchaser or of the public generally.

Heretofore one of the usual practices employed in connection with the display and 10 exhibition of rugs has been to individually suspend a number of rugs from heavy overhead frames or racks arranged to swing about a common vertical axis. Due to the fact that the weight of the rugs is often considerable, these frames or racks are subjected to 15 great stresses, it being necessary, in order to offset this, to employ special reinforcing and strengthening members. Not only do these latter members make the racks heavy and 20 cumbersome, and consequently difficult to move and at the same time expensive to construct, but there is the further and important objection that the rugs, being suspended more or less vertically, cannot be viewed satisfactorily by the customer, inasmuch as the 25 coloring of the rug depends largely upon the angle which the light makes with the nap.

This last mentioned objection has long been realized by those who display and exhibit 30 rugs with the result that resort has been had to the simple idea of stacking the rugs in piles in order that they may be viewed in the position in which they are ordinarily used. However, the rugs, being of considerable 35 weight, are difficult to handle when stacked one upon the other, it being usually necessary to employ two men solely for the purpose of throwing each rug back upon itself in order to bring to view the next rug in the stack.

40 Needless to say, this procedure is quite expensive, due to the cost of the labor involved and also due to the time consumed in going through a stack of rugs of moderate number. It is true that ideas have been advanced from 45 time to time having in mind to obviate the objections encountered in displaying and exhibiting rugs, but until this invention it does

not appear that the problem has ever been entirely solved. One of these ideas has been to fasten a number of rugs together, end for end, 50 to form a continuous strip adapted to be wound upon one reel and unwound from another reel. A disadvantage of this arrangement has been that the number of rugs which can be so fastened together for subsequent 55 winding upon a reel is limited, especially where the rugs are of good quality having relatively heavy naps, inasmuch as the diameter of the rugs on either the driving or driven roll soon becomes too large to be conveniently handled. Further, there is the disadvantage which is attendant upon fastening the rugs together, with the still further disadvantage that in such an arrangement the 60 tendency is to subject the rugs to an undesirable tension. 65

It is among the principal objects of the present invention to obviate the aforementioned difficulties and objections by providing a mechanism which is adapted to display 70 a series of rugs with greater facility than has ever been possible heretofore.

Another object of the invention is the provision of an apparatus for displaying rugs which is so arranged as to permit the rugs 75 to be successively presented to the view of the observer at an angle which most satisfactorily brings out the color and design of the rug under examination.

A further object of the invention is the 80 provision of an apparatus which is operable automatically to successively exhibit a series of rugs in a horizontal position or in a position making any desired angle with the horizontal.

85 A still further object of the invention is to provide a mechanism for successively displaying a series of rugs, the mechanism being so designed as to receive said rugs without subjecting them to undesirable tension, and 90 being further provided with means arranged to permit each of the rugs to be quickly and conveniently secured in position or as quickly removed therefrom.

Other objects and objects relating to details of economy and construction will appear more fully hereinafter.

The invention consists substantially in the construction, combination, location and relative arrangement of parts, all as will appear more fully hereinafter, as shown in the accompanying drawings, and as finally pointed out in the appended claims. It is to be understood that the drawings show and the following specification describes a preferred form of the invention and that changes may be made from time to time without departing from the principles of the invention as defined in the claims.

In the said drawings:

Figure 1 shows a top plan view of the major portion of an apparatus embodying the principles of this invention;

Figure 2 is a side elevation of the apparatus;

Figure 3 is an enlarged plan view showing a portion of the apparatus;

Figure 4 is a section taken on the line 4—4 of Figure 3;

Figure 5 is a section taken on the line 5—5 of Figure 3;

Figure 6 is a diagrammatic view of a modified form of apparatus; and

Figure 7 is a view taken on the line 7—7 of Figure 1.

Referring more particularly to the drawings, it will be seen that the apparatus generally is indicated by the reference numeral 10. Suitably journaled at the rear end of the apparatus are a number of horizontally extending rollers 11, these rollers 11 being vertically spaced one above the other a substantially uniform distance apart. Each of these rollers 11 is provided with a toothed sprocket wheel 12 at the opposite end thereof. Suitably journaled at the forward end of the machine are a corresponding number of rollers 13, these latter rollers being also vertically spaced one above the other a substantially uniform distance apart. As in the case of the rollers 11, the rollers 13 are also provided with sprocket wheels 14 at opposite ends thereof, these sprocket wheels 14 being respectively located in such manner that their axes lie in horizontal planes lying between the planes of the axes of the rear sprocket wheels 12.

In the particular form of construction shown in Figures 1 and 2, a transversely extending roller 15 is provided which is located a substantial distance forwardly of the vertical plane of the rollers 13. This forwardly disposed roller 15 is also provided with sprocket wheels 16 at opposite ends thereof, it being understood that all of the rollers lying to one side of the apparatus lie in a common vertical plane while all of the rollers lying to the other side thereof lie in a plane paralleling said vertical plane.

Arranged to pass back and forth over the sprocket wheels lying to either side of the apparatus are a pair of endless conveyor chains 17. Due to the fact that the wheels 14 are staggered with respect to the wheels 12, the greater portions of these chains travel along vertically spaced substantially parallel paths, as appears most clearly in Figure 2. The inclined sections 18 of these chains, however, extend forwardly and pass over the sprocket wheels 16 of the foremost transversely extending roller 15. Preferably, a pair of upper and lower rollers 19 and 20 are located immediately in front of the forwardly disposed set of rollers 13, these rollers 19 and 20 being respectively provided with sprocket wheels 21 and 22 constituting idlers over which the chains pass.

The rear set of rollers 11 projects to one side of the apparatus, as at 23, and secured to these laterally projecting portions of the rollers 11 are a series of vertically arranged driving wheels 24, the teeth of which are engaged by a driving chain 25 arranged to commonly drive all of said driving wheels in unison. A gear 26 is keyed or otherwise suitably secured to one of the rollers 11, preferably the lowermost one of the series, this gear being arranged for entrainment with the driving gear 27 carried upon the shaft of a motor 28. It will be seen that by virtue of the arrangement just described, the conveyor chains 17 will be caused to travel back and forth over the several sets of rollers in the manner best shown in Figure 2, it being understood that these chains are uniformly spaced apart throughout their entire extent and that their speeds of travel are exactly the same. While under ordinary circumstances the conveyor chains may be caused to travel in the desired manner, solely through the operation of the driven gear 26 which is secured to the lower roller 11, this latter roller being then the only driving roller, it is preferable to employ the driving chain 25 inasmuch as the latter serves to convert all of the rollers 11 into driving rollers, thereby facilitating the travel of the endless conveyor chains 17.

The several sprocket wheels on either side of the apparatus, and accordingly the conveyor chains 17, may be spaced apart any desired distance depending entirely upon the width of the rugs which are intended to be accommodated in the apparatus, all of which are of the same or approximately the same width. Extending transversely across the apparatus with the opposite ends thereof secured in any desirable manner to the chains 17 are a plurality of bars 29, one such bar being preferably employed for each end of a rug 30. (See Figure 1.) Obviously, these bars may be spaced apart any desirable distance, depending upon the lengths of the rugs, it being preferable to arrange them in such manner that when the rugs 30 are superim-

posed one above the other, as shown in Figure 2, the bars will form two sets lying respectively in the vertical planes of the rollers 11 and 13. The end of each bar is preferably 5 slotted, as at 31, for reception of the inwardly projecting lugs 32 carried at longitudinally spaced intervals by the conveyor chains 17. Suitable pins 33 pass through the slotted ends of the bars and through the 10 lugs 32 for maintaining the bars in fixed position with respect to the conveyor chains.

Each of the bars 29 has secured thereto, preferably by rivets 34, a plurality of spring pressed clamps 34', between the jaws of which 15 is firmly grasped the end of a rug 30 in the manner most clearly shown in Figure 5. If desired, a plurality of similar spring pressed clamps 35 may be provided for firmly grasping the side edges of the rugs, these 20 clamps 35 being secured, by the pins 36, to projecting lugs 37 carried by the chains 17, these lugs 37 being similar in all respects to the lugs 32 between which the bars 29 are supported. Preferably, the pins 33 and 36 25 are removable in order to more readily permit changes being made in the longitudinal spacing of the bars 29 and side clamps 35 when the lengths of the rugs are varied.

In the particular arrangement shown in 30 Figure 2, a total of twenty rugs is accommodated in the apparatus, eighteen of these rugs being normally arranged in superimposed, or stacked relation, while the remaining two rugs are located upon the forwardly extending 35 inclined portions of the conveyor. It is the upper of these two rugs which is on view before the purchaser, this rug being displaced by the one next succeeding it and so on as long as the motor 28 is operated and the conveyor 40 chains 17 continue to travel over the sprocket wheels. Obviously, it is a simple matter to stop the motor to give the purchaser an opportunity to more closely examine that rug in which his interest enters.

It is, of course, possible by the use of one 45 or more rollers to change the course of travel of the rugs through the actual exhibiting section of the apparatus, Figure 6 illustrating how one such change may be effected. In the arrangement shown in this figure, the rug under observation is designed to travel in a substantially horizontally extending plane, the arrangement being in all other respects substantially similar to that shown in Figures 50 55 1 and 2.

The advantages of the arrangements herein described and illustrated are numerous and quite obvious. By reason of the fact that each rug is individually secured in position 60 between a pair of cross bars 29, the rugs are each subjected to a minimum tension, thus avoiding to great extent, if not entirely eliminating, all wear and tear during the continual process of exhibiting them to pros-

spective purchasers. The apparatus materially facilitates the rapid exhibition of all of the rugs accommodated therein at the same time that the customer is given an opportunity to examine them more leisurely if he so desires and in a much more satisfactory 65 manner than has ever been possible heretofore. Still further, the rugs may be removed from the apparatus and others readily substituted in their place as the occasion warrants. And still further, the apparatus is 70 75 not only compact and efficient in operation, but is also adaptable for exhibiting rugs of various widths and lengths.

It is to be understood, of course, that various changes may be made from time to 80 time without departing from the real spirit or principles of the invention, and it is accordingly intended to claim the invention broadly as well as specifically, as indicated by the appended claims.

What is claimed as new and useful is:

1. In a rug exhibiting apparatus, a plurality of rollers arranged in two spaced series, a pair of laterally spaced conveyor elements having longitudinally spaced transverse bars extending therebetween, said elements being arranged to simultaneously travel back and forth over said series of rollers along substantially parallel paths, means for directing the travel of said elements and bars along the path substantially equal in length to that of a rug and extending forwardly of said parallel paths, means for detachably supporting a plurality of rugs between said conveyor elements and bars, and means for transmitting motion to said elements whereby to cause said rugs to successively travel over said horizontal path.

2. A rug exhibiting apparatus, a plurality of rollers arranged in two spaced series, an endless conveyor having bars extending transversely therebetween for travelling back and forth over said rollers along a number of vertically spaced substantially parallel paths, an auxiliary roller spaced in advance 105 of said series of rollers for directing travel of said conveyor over a substantially horizontal path extending forwardly of said parallel paths, means for supporting a plurality of rugs upon said endless conveyor and between adjacent pairs of said transverse bars, said forwardly extending path being of a length sufficient to present only one rug to view in its entirety at any time, and means for transmitting motion to said conveyor 110 whereby to cause said rugs to successively travel over said forwardly extending horizontal path.

3. In a rug exhibiting apparatus, a plurality of rollers arranged in two spaced series, a pair of laterally spaced conveyor chains having transverse bars extending therebetween for connecting the same to

gether, said chains being adapted to travel back and forth over said rollers such that portions thereof traverse substantially parallel paths, means for securing a rug between said chains and adjacent pairs of said transversely extending bars, and means for removably securing said transverse bars in ad-

justed position between said chains whereby said bars may be spaced apart a greater or less distance. 10

In testimony whereof, I have hereunto affixed my signature.

GEORGE J. SEGAL.
